SPACE HEATER

Robert B. Evans, Grosse Pointe, and Eugene F. Farrell, Detroit, Mich., assignors to Evans Products Company, Detroit, Mich., a corporation of Delaware

Application August 5, 1939, Serial No. 288,542

11 Claims. (Cl. 126—110)

This invention relates to space heaters or the like, and particularly to the floor-supported cabinet type of unit space heater having a combustion unit to heat air to a high temperature and an air circulating fan therein for circulating this high temperature air through rooms, small homes, or the like. Preferably, the fan is in the lower part of the cabinet adjacent an opening located closely above the floor so that the fan will draw air down past the combustion-heating unit and will discharge a stream of the high temperature air across and close to the room floor. The several parts are so arranged that upon non-operation of the fan the space heater may operate by the natural upward convection circulation of air therethrough.

This invention also relates to space heaters of the general character shown in our prior application S. N. 232,502, filed September 30, 1938, and the application of Schueder and Farrell, S. N. 259,094, filed March 1, 1939, and it embodies features disclosed and claimed in these prior applications. The general arrangement and structure of the cabinet, its doors, the heating drum and its oil burner, the fuel controls, the oil tank with its mounting and cooling, the transverse partition and the like are, or may be, generally similar to our prior application noted above. The feature of the fan-forced stream of high temperature air across and close to, but safely above, the room floor is common to our prior application and the application of Schueder and Farrell, both noted above. The additional feature whereby this air discharge is caused by a blower unit alongside of and the discharge of which is directly out through the cabinet opening, is also embodied in the last mentioned application.

In general, the objects of the present invention are to provide an improved and simplified unit space heater having a fan-forced and low level, but safe, discharge of high temperature air across and close to the floor. More particularly, the objects of this invention are to provide such a space heater in which horizontally directed, propeller type fan or fans are positioned at the same level, closely alongside of, and discharging directly out through the low opening or openings which are located at the bottom (preferably in the front) of the cabinet closely above the room floor so that the fan means will draw air down past the combustion-heating unit and then discharge it out through the low level openings, and so that when the fan is not operating the air may rise through the cabinet

by natural upward convection and circulate into the room from the cabinet's upper opening.

Other and more detailed objects and advantages will be apparent from the following description and the drawings, in which:

Fig. 1 is a front elevation view of a space heater embodying our invention, the outer casing being broken away to show internal parts;

Fig. 2 is a vertical sectional view taken on the line 2—2 of Fig. 1;

Fig. 3 is a transverse sectional view taken on the line 3—3 of Fig. 2;

Fig. 4 is a fragmentary view similar to Fig. 1 and showing the lower end of another embodiment of our invention; and

Fig. 5 is a view taken transversely of Fig. 4 just above the level of the fan and motor.

In the drawings, Figs. 1, 2 and 3 show one embodiment of the invention.

The outer body or casing 1 is formed of sheet metal formed and secured in any conventional or desired manner. This casing 1 is of substantially rectangular transverse cross-section and is in the form of the so-called "low-boy" type of cabinet. The cabinet is supported at its corners and is spaced above the floor by feet 3 which are sheet metal expansions. The bottom plate 2 is suitably secured to close the bottom of the cabinet completely except for the combustion air intake openings 22 and the space under the oil tank 5 or on the other side of the partition 6, which space is left open.

The tank 5 for liquid fuel, such as oil, is removably mounted by suitable clips on and spaced from the outermost of the two insulatingly spaced, sheet metal, partition plates 6. Thus this tank 5 is insulated from the heat and is also cooled by the air which rises freely through the open bottom up and around the tank. This tank 5 has a suitable swing-out filling spout and a level indicator. Access to the filling spout is had through a conventional door 5a. The partition plates 6 are suitably secured to the base plate 2 and brace the shell 1. The combustion-heating unit is designated as a whole by the numeral 4. It includes a sheet metal heating drum having a top 8 and upright side walls 7 supported and closed by bottom plate 2. Supporting partition 13 is suitably secured to the walls 7 and carries burners 14 in corresponding openings therein. For an oil burner unit, these burners 14 are the conventional pot type. Thus the space in the drum above 13 forms an expansion chamber and the space below it forms a combustion chamber. A sheet metal radiation

heat shield or drum-enclosing wall 32 is uniformly spaced about the drum 7-8 and supported by suitable brackets 30 and the base plate 2 so that this wall defines two upwardly extending, air heating passageways, both of which communicate freely with the large area upper opening 26. It will be apparent that the innermost passageway (inside wall 32) is of smaller cross-sectional area and also at a much higher temperature.

The oil is supplied from the tank 5 through pipe 15 to a conventional regulating valve and level-maintaining float unit 18 which is carried by a suitable supporting strap 18a. The oil supply for each burner is regulated by a rotary valve, and these valves are manually controlled by shafts 19 and 21 which extend up through suitable controls which are not shown herein but may be as disclosed in our prior application or in other desired arrangements. Pipes 16 and 17 carry the oil to each of the burners 14.

Base plate 2 has combustion air inlet openings 22 which may have regulating means, such as the pivoted adjustable plates or dampers 23. The products of combustion expand and give up heat in the expansion chamber and rise through the flue or stack connection 24 which extends through corresponding openings in the wall 7 and the shield 32. A stove pipe fitting 25 which extends in through a corresponding opening in the shell 1 is removably connected to flue connection 24 and communicates with the usual chimney or stack.

The cabinet top 27, which may be integral as shown, has openings 26 to form a large area grille. These openings may be formed in the sheet metal top by cut and stamped or bent down portions, as shown.

The lower end wall of the cabinet shell adjacent and underneath the oil tank 5 has an air inlet grille 29 which may be formed integral with the shell wall and with upright vanes to strengthen the cabinet. This opening 29 provides an additional inlet for cooling air to rise up around through valve float unit 18 and the oil tank 5 to cool them and then to rise out through the top openings 26 or else, when the fans are running, to be all or partly drawn down on the other side of the supporting and insulating partition 6. It will be apparent that this separate, upwardly extending passage or chamber having an open top or bottom, which contains the oil tank and oil controls, will have a natural chimney action or convection circulation keeping it cool.

The lower front wall of the cabinet shell has a circular, stamped-in socket opening 55 which receives and frictionally retains a large area opening grille 28 which may be formed by cutting and stamping-in vanes from the curved bezel 54. It will be noted that these upright vanes point in generally towards a common center so that they will laterally spread or fan out the fan forced air stream.

Access to the interior of the heating unit and to the burners may be had through conventional cabinet door 56, an opening 57 in the shield or drum-enclosing wall 32, and the heating drum door 58.

A multi-bladed propeller type fan 33 is driven by an electric motor 34 which is mounted so that it is removed from and insulated from the heat of the combustion unit and so that it may be easily serviced. The motor is mounted and shielded by a cup member 35 mounted in an

opening or notch 39 of the shell 1 and having a radial flange 40 overlapping the edges of this opening 39. The bottom of cup member 35 is spaced from the shield wall 32 by sound and heat insulating devices 36. Bolts 37 pass through wall 32, sleeves 36, member 35, and lugs 38 extending from the electric motor to hold these parts in place.

The lower front side of shield wall 32 has a circular opening 43 having a cylindrical flange 42 forming a short duct or air directing cowling to contain the propeller type fan 33 which is of slightly smaller diameter. Thus this short air directing duct 42 will improve the directional effect of the fan and reduce the diffusion or radial discharge from its blades.

The fan 33 is secured on shaft 44 which is journaled in a bearing 45 rigidly held in the interior of the opening 43 by a spider 46 comprising straps 47 which embrace the sides of the bearing 45 and which are bent out at their ends to form feet 48 riveted or otherwise connected to flange 42. The two straps 47 may also be suitably connected together.

A connecting shaft 49 extends alongside of and between the two burners 14 and connects the motor shaft 51 and the fan shaft 44 by suitably yieldable and resilient muff couplings 52 formed to afford a heat and noise insulation and to also act to a limited extent as misalignment couplings. It is desirable to prevent the transmission of heat to the motor along its shaft, and the fan and motor assembly noise will be also reduced by such couplings.

The grille 28 is at the bottom of the cabinet spaced slightly above the floor by feet 3, and the fan 33 and directing duct 42 (which are nearly the same diameter) are quite close to grille 28 and at the same level so that the fan and its cowling duct will throw a horizontal stream of high temperature air directly out through grille 28 (which will spread or fan it out horizontally) in a stream which is close to but spaced sufficiently above the floor to prevent dangerous over-heating thereof since it will not strike the floor close to the cabinet or until the stream has been cooled and diffused to a sufficient extent. It may be noted that the height of the fan 33 above the floor is less than its diameter and, in fact, is roughly equal to its radius in this specific embodiment.

Thus, during fan operation, the fan will, if it is powerful enough, draw all of the air down through the innermost and smaller area and hotter passageway (between wall 32 and drum walls 7) and will draw some or all (depending on its power) of the partly heated air rising up through the separate oil tank passageway. When the fan is not running, outside or room air will enter grille 28 and, through opening 43, will rise up through the inner air heating passageway by normal convection circulation as in a conventional air circulating space heater. Some, or a small amount of, the air entering grille 28 may rise up through the space between flange 42 and the shell 1 and go up the outer and larger and lower temperature passageway.

The lower end of the cabinet shell, remote from the oil tank, may, if desired, have an air inlet grille 31 which is similar to grille 29. Also the lower end of the shield wall 32 may, if desired, have relatively small or rather restricted openings or cut-out notches 59, as shown. If neither opening 31 nor openings 59 were present, the lower end of the air heating passageway be-

tween the wall 32 and the cabinet 1 would be closed and would form a dead air space with no appreciable air circulation during fan operation or during non-fan operation.

Thus it will be apparent that instead of being relatively small or restricted, openings 59 may be eliminated. Thus each upwardly extending air heating passageway has its own bottom opening so that, during fan operation, air is drawn down inside of wall 32 and discharged out of grille 28 while air is entering 31, rising up between 32 and 1 and rising out through grille 26 or, in whole or in part, depending up on the power of the fan, being drawn down into the inner passage. When the fan is not running, air enters and rises through each passageway through 28 and 31 respectively. If, as shown, relatively small openings 59 are used with opening 31, the inlet opening area to the inner heating passageway is increased for its normal upward or non-fan operation and, during fan operation, some, or a part, of the air discharged by the fan may be pulled in through 59 which is small enough to permit air being drawn down through the inner passageway. If opening 31 were not used, then, during fan non-operation, air would enter 28, some rising up the inner passageway and some passing through 59 and rising up the outer passageway.

Figs. 4 and 5 show another embodiment of this invention. Since the features of the upper portions of the heater unit are the same as in Figs. 1, 2 and 3, they are not shown herein. Also many of the features of this embodiment are the same as in Figs. 1, 2 and 3 and carry the same reference numerals and thus are not further described herein.

The fan shaft bearing 45 is supported by a tripod spider 61, the straps 62 of which are bent at their ends and secured to the flange 42 by screws 63 or other suitable removable fastenings. The electric motor 64 is mounted on a suitable strap 64a across the opening below the oil tank so that the motor is separated and insulated from the combustion unit heat and is cooled by the rising current of air in this end passageway. The motor shaft carries two pulleys 66 and 74. A conventional V-belt 65 connects pulley 66 and pulley 67 on the fan shaft 44. A second propeller type fan 71 is secured on shaft 68 which is journaled in a support pedestal 69 bolted on the base 2. The other end of shaft 68 fixedly carries a pulley 72 which is driven from pulley 74 by a short V-belt 73.

Grilles 75 and 78 are formed in convex bezels 76 and 79 and frictionally retained in sockets 75 and 81 respectively, all as disclosed with respect to grille 28. These two grilles 75 and 78 and their fans or blower units are also located at the same height and spread or fan out the discharge like grille 28. As illustrated in Figs. 3 and 4, the fuel valve unit is mounted behind the electric motor 64.

Thus, in this second embodiment, fan 33 draws its stream of high temperature air drawn down around the drum walls 7 just as disclosed with respect to Figs. 1-3 inc. Fan 71, however, draws its air down the larger area outer heating passageway (between shell 1 and wall 32) at a lower velocity due to the larger area which matches the lower temperature and consequent lower heating rate in this outer passage. Since the temperature of the air discharged by fan 71 is not so high, a directing cowling or duct like 42 is not as necessary. This short duct 42 may

also be considered as a blower discharge directing nozzle.

As disclosed with respect to Figs. 1-3, inc., and if desired, the lower end of the wall 32 and the shell 1 may have the relatively small openings 59 and grille 31, respectively, to aid in preventing dead air spaces and in opening up the bottom intake area for upward convection circulation. However, it will be apparent that in this embodiment both openings 59 and 31 can be eliminated since each fan can draw hot air down through its own separate heating passageway and each fan opening or grille can serve as an air inlet for the upward convection circulation when the fans are not running. Similarly, as noted with respect to Figs. 1-3 inc., either one of opening 31 or openings 59 can be eliminated if desired.

It will also be apparent in each embodiment that the fans may be used to circulate air in summer when the heating unit is not used.

While only two embodiments of this invention are illustrated and described in detail herein, it is to be understood that various changes and modifications may be apparent to those skilled in the art without departing from the spirit and scope of this invention, and therefore the same is only to be limited by the scope of the prior art and the appended claims.

We claim:

1. A unit space heater comprising an upright cabinet adapted to be supported on the floor of the room to be heated and having an upper opening, an upright combustion drum spaced within said cabinet and an upright enclosing wall spaced about said drum to provide inner and outer, upwardly extending, air heating passageways between said drum and said wall and between said wall and said cabinet respectively, each passageway having an upper opening communicating with said upper cabinet opening, a lower opening for said outer passageway, an opening through the lower end of said enclosing wall and a corresponding opening through said upright cabinet adjacent its bottom, an upright propeller-type fan associated with said last two openings to pull air down through said inner passageway and discharge it directly out into the room.

2. A unit space heater for a room or the like comprising an upright cabinet casing having an open top and a circular opening in the lower portion of its front wall, feet supporting the lower end of said casing close above the room floor, a liquid fuel pot burner in the lower portion of said casing at the level of said circular opening, an upright heating drum for confining the products of combustion above said burner, an upright, spaced, enclosing wall for said drum providing an inner, open top, upwardly extending, air heating passageway around said drum and between it and said wall, a bottom plate closing the bottom of said inner passageway, said wall being spaced inwardly from said casing to form an outer, open top, upwardly extending, air heating passageway, a lower air inlet for said outer passageway so that air may enter and rise up said outer passageway by convection circulation, a horizontal axis, propeller-type fan close to and discharging directly out through said circular opening and between it and said burner, a cowling about said fan communicating through an opening in said enclosing wall so that said fan can draw heated air rising in said outer passageway down through said inner passage-

way and discharge it into the room through said circular opening.

3. A unit space heater for a room or the like comprising an upright cabinet casing having upper and lower openings including an opening substantially at the bottom of its upright front wall, feet supporting the lower end of said casing above but close to the room floor, a burner containing, upright heating drum in and spaced from the casing walls to form an upwardly extending, air heating passageway of large cross sectional area and communicating with said lower and upper openings for upward convection circulation of air therethrough, partition means forming with said upright drum walls a downwardly extending, air heating passageway smaller than and within said larger passageway and having an upper air inlet within said larger passageway to supply heated air thereto, blower means associated with the lower end of said inner passageway to draw air down through it and along said upright heating drum and having a short air discharge directing pipe at the same level as and pointing horizontally toward said front bottom opening to discharge a stream of high temperature air horizontally to and out through said bottom front opening across and above, but close to, the room floor.

4. A unit space heater comprising an upright, floor supported cabinet having an upper opening and containing an upright combustion drum and an upright enclosing wall spaced about said drum and spaced inwardly from said cabinet to provide inner and outer upwardly extending and open top air heating passageways, a lower cabinet opening for said outer passageway to admit air for upward convection circulation therethrough, corresponding lower openings in said enclosing wall and said cabinet wall for said inner passageway, a short, horizontal, outwardly extending, air directing duct or fan cowling on said wall about its lower opening, and an upright propeller-type fan therein to draw air down through said inner passage and discharge it out through said lower cabinet opening in a substantially horizontal stream.

5. A unit space heater comprising an upright, floor supported casing having an open top and containing an upright combustion heating unit and one upright enclosing wall spaced about said heating unit and spaced inwardly from said casing to provide inner and outer upwardly extending and open top air heating passageways, an opening means for said outer passageway in the lower portion of said casing and opening means for said inner passageway including corresponding openings in the lower portions of said wall and said casing, and blowers in said casing and associated with each passageway to circulate air downwardly through each air heating passageway and to discharge it out of its lower opening means.

6. The organization set forth in claim 5 in which each lower opening means is horizontally directed and is close to but spaced a safe distance above the floor and in which each blower is an upright propeller-type fan close behind its lower opening.

7. The organization set forth in claim 5 in which a blower driving motor is positioned remote from and is insulated from said heating

unit and each blower is connected to be driven by said one motor.

8. A unit space heater comprising an upright, floor supported casing having an open top, two liquid fuel burners spaced side by side in the bottom of said casing, an upright expansion drum for the products of combustion over said burners and spaced inwardly from said upright casing to form an upwardly extending, open top, air heating passageway, an opening in the lower front wall of said casing communicating with said passageway, a fan close behind and discharging air out through said opening after pulling it down said passageway, a fan driving motor mounted on the opposite side of said casing, and a fan-motor connecting shaft extending alongside of and between said burners.

9. A unit space heater for rooms or the like comprising an upright casing having upright side walls, an open top, and means supporting its lower end upon and close above the room floor, a lateral opening through the lower portion of the upright side wall of said casing adjacent but spaced above the room floor, an air heating, upright, combustion drum spaced within said casing forming a narrow space to provide an upwardly extending air heating passageway, and an upright propeller-type fan in said narrow space and extending alongside of the lower side portion of said drum and close behind said lower opening to pull air down through said passageway around said drum and to discharge it directly out into the room through said lower opening.

10. A unit space heater comprising an upright, floor supported casing having an open top and upright side walls spacedly enclosing an upright burner-heating unit forming a narrow space to provide an upright air heating passage therebetween, a lateral opening through the lower portion of the upright side wall of said casing adjacent to but spaced above the floor, an upright propeller-type fan in said narrow space extending alongside of the lower side portion of said burner-heating unit close behind said opening to pull air down through said passageway around said drum and discharge it directly out through said lower opening, a driving electric motor mounted on the opposite, outer side of said casing to protect it from the heat from said burner-heating unit, and straight shaft means directly connecting said fan to said motor.

11. A unit room heater comprising an upright, open top casing having an upright front wall and having means to support it on the room floor, an upright combustion drum spacedly enclosed therein to form an upright, high temperature, air heating passageway with an open top, a burner in the lower end of said drum, an access door in said drum above said burner, a co-operating access door in the front wall of said casing, an upright, horizontally discharging, propeller-type fan drawing air through said open top and down said passageway and positioned in said passageway below said access doors alongside of the lower side portion of said drum, and a discharge grille in said casing in front of said fan.
